(No Model.)

I. B. KELLER.

SHIRT.

No. 341,017.

Patented May 4, 1886.

UNITED STATES PATENT OFFICE.

ISAAC B. KELLER, OF LEBANON, PENNSYLVANIA.

SHIRT.

SPECIFICATION forming part of Letters Patent No. 341,017, dated May 4, 1886.

Application filed December 12, 1885. Serial No. 185,506. (No model.)

To all whom it may concern:

Be it known that I, ISAAC B. KELLER, a citizen of the United States, residing at Lebanon, in the county of Lebanon and State of Pennsylvania, have invented certain new and useful Improvements in Shirts; and I do hereby declare that the following is a full, clear, and exact description of the same, reference being had to the annexed drawings, making a part of this specification, and to the letters and figures of reference marked thereon.

Figure 1 of the drawings is a back view of a shirt made in conformity with my invention. Fig. 2 is a similar view with the sleeves and collar-band removed, and the lap-over and one of the back yoke-sections partly broken away; Fig. 3, a sectional view, on an enlarged scale, taken on line *x x* of Fig. 1.; Fig. 4, a sectional view, on an enlarged scale, taken on line *y y*; Fig. 5, detail views of the several strips forming the lap-over and joining-pieces; Fig. 6, a similar view of one of the inside yoke-sections, and Fig. 7 a detail view of one of the extension re-enforcement yoke sections.

The present invention has relation to certain new and useful improvements in shirts; and the object thereof is to provide means whereby the shirt is materially increased in strength around the shoulders or yoke, and insure its fitting much nicer, as well as more comfortable to the wearer. These objects I attain by the construction substantially as shown in the drawings, and hereinafter described and claimed.

In the accompanying drawings, A represents the body of the shirt, and B the sleeves thereof.

To the upper or shoulder portions of the back of the shirt are secured by stitching, in the ordinary manner, yoke-sections C, of the form shown in Fig. 6, each section extending across the back of the shirt from the slit or opening therein to the sleeve, where it joins the body at the shoulders. Over these sections C are secured by stitching re-enforce sections D, of the form shown in Fig. 7, which also extend across the back of the shirt and down to the armpits thereof, being stitched into the sleeve-holes with the sleeve. The neckband *a* is provided with a button-hole, *b*, as is also the re-enforce section immediately

above the lap-over, as shown at *c*, in order to well secure the back of shirt from gaping. The lap-over consists of three distinct pieces or sections, combined and attached as follows, 55 viz: The left side of the slit or opening in the back of the shirt is secured the joining piece or strip E along its straight edge, which forms the lap-over, and which is strengthened by stitching on the outside of strip E a lap-over strip F, thereby securing utility, strength, and durability, a protection-piece, *d*, secured transversely across the lower end of the lap-over strip F, resisting the possibility of tearing down the back-opening. This protection 60 piece or stay *d*, I lay no claim to in the present application, as it forms the subject of an application filed April 8, 1886, Serial No. 198,181.

That portion of the shirt-back coming upon 7C the inner side of the slit or opening has stitched to its edge the strip G, which, together with the strips E F, forms a perfect lap-over, which, when buttoned at *b c*, will prevent the opening in the back from gaping.

The strip E, which forms the joining-piece to the left edge of the slit in the shirt-back, serves as a foundation or inside lining to the lap-over strip F when the latter is stitched to its place.

The addition of the inner yoke-section, C, and re-enforce D, secured to and over the inner section, form together a strong re-enforcement underneath and back of the arms, thus rendering the shirt more durable, nicer fitting, 85 and in every way superior to the shirts in ordinary use.

I am aware that it is common to provide a shirt in which a portion of the sleeve material extends up to the collar-band; also that it is 9C not new to extend a yoke portion out to the armhole of the shirt. My invention differs from either or both of these constructions. I provide a shirt with a yoke, C. In addition to the body A and yoke C, I provide a re-enforce, D, which covers the yoke and extends over the outside thereof to the armhole, and is sewed in with the sleeve. It also extends down over a portion of the body A to the arm-pit.

What I claim as new is—
The shirt described, consisting of the body

A and yoke C arranged as shown, and the re-enforce D, extending from the collar-band to the sleeve-hole exterior to the yoke and stitched in with both collar-band and sleeve, a portion 5 of the re-enforce extending over the body A and along the armpit, and the whole arranged to serve as set forth.

In testimony that I claim the above I have hereunto subscribed my name in the presence of two witnesses.

ISAAC B. KELLER.
